UNITED STATES PATENT OFFICE.

HOMER A. KING, OF SPRINGFIELD, MASSACHUSETTS.

VELOCIPED.

SPECIFICATION forming part of Letters Patent No. 349,802, dated September 28, 1886.

Application filed May 10, 1886. Serial No. 201,726. (No model.)

To all whom it may concern:

Be it known that I, HOMER A. KING, a citizen of the United States, residing at Springfield, in the county of Hampden and State of Massachusetts, have invented new and useful Improvements in Velocipedes, which improvements are fully set forth in the following specification, the accompanying drawings making part of the specification.

10 My invention relates to improvements in bicycles, tricycles, and quadricycles; and it consists in an improved construction of the steering-head; in an improved handle-bar and brake; in a new construction of a hollow felly-
15 rim; to improved rubber tires and improved means of securing the rubber tire to the felly; to improved means of securing anti-friction rollers in place, and improved means of securing connection between the propelling-drums. These improvements are described in connection with some of my improvements more fully described in my Patents Nos. 327,397, 327,954, and 341,383.

20 Referring to the drawings, similar letters of reference indicate corresponding parts.

Figure 1 is a side elevation sectional view of my high-seated bicycle having the steering-wheel in front. Fig. 2 is a view of the steering-head, neck, backbone, and fork shown in Fig. 1. Fig. 3 is a sectional elevation of Fig. 2, taken in the line M G". Fig. 4 is a section of Fig. 3 with my anti-friction spool-bearings added. Fig. 5 is a rear view of my improved handle-bar, which bends downward and backward. Fig. 6 is a top view of Fig. 4 with my brake-handle added. Fig. 7 shows the rollers used in making hollow felly-rims shown in Figs. 8, 9, and 10. Figs. 7, 8^a, 9, and 10 show the construction 30 of and the completed double protuberant hollow rim, made of one piece of metal, united by lapping and brazing on the inner convex side nearest the hub, and rubber tire of suitable form. It may have side projections, as shown, 35 constructed on the outer or upper portion by the rollers and afterward bent down to the position as shown. Fig. 8^a shows my rubber tire contracted as made, and by broken lines its position when in place in the felly-rim,

the contraction on the inside and the openings fitting over the side projections serving to hold it in place, and the contraction on the outer surface preventing its being easily cut by sharp stones. Fig. 9 shows the two grooves formed by straight lines as shoulders for the 50 rubber tire. Fig. 10 shows by broken lines the bottom of the rubber bed flat and its form when slightly convex. Fig. 11 shows a new form of the hub *y* and spoke-flange *K*, which may be thin and flexible near its outer periphery. It also shows inclined rollers secured in place at each end on projection or axle. These projections, formed on each end of the rollers or by an axle running through each roller and projecting at each end into 60 cavities in a collar which touches only these projections, hold the rollers apart and in place. Fig. 12 shows another form of hub with one propelling-drum *B* secured to the axle and one retracting-drum *B'*, whereby the 65 depression of one lever on one side of the drive-wheel raises the lever on the other side of the drive-wheel.

A part of these improvements was described in the original application, filed January 20, 1886, Serial No. 189,181, which has been divided into three separate applications. Whatever, therefore, is in this application that is claimed in either of the other two applications I hereby disclaim.

Having thus described my invention, what I claim as new, and desire to secure by Letters Patent, is—

1. The combination of the backbone *M'*, neck *M*, collar *C*, steering-head *c*, and inclined spool-bearings between the collar *C* and the steering-head *c*, substantially as shown.

2. The rearwardly-inclined handle-bar, in combination with the brake *G*, made of one piece of metal and secured by a collar near 85 the center to the handle-bar, substantially as shown.

3. A hollow felly-rim constructed of one piece of metal, with an outer central elevation in the rubber-tire bed, and bent inward 95 at *v'* and *v''* and lapped, forming a protuberance toward the hub, substantially as set forth.

4. A hollow felly-rim constructed of one

piece of metal, with a central elevation in the rubber-tire bed, and with projections on each side of the central elevation, substantially as and for the purpose set forth.

5. Inclined adjustable rollers running in a circle between an inclined surface on the outside of the circle and an inclined surface on

the inside of the circle, and with the rollers held apart at each end by a collar, substantially as set forth in Fig. 11.

HOMER A. KING.
